UNITED STATES PATENT OFFICE

HARRY E. MUSSWHITE, OF PORTLAND, OREGON

FLUID MOTOR

Application filed September 19, 1928. Serial No. 306,962.

My invention relates to improved radial blade fluid motors driven by the continuous flow of fluid pressure.

Radial blade motors have heretofore been commonly constructed with an eccentrically mounted revoluble member of lesser radius than the housing arranged in contact at a point with the wall of the motor housing, thus forming a seal between the intake and 10 exhaust ports.

This type of motor has not, in my opinion been efficient, for the contact of the revoluble member with the wall of the housing is only at a point so that leakage of fluid between 15 the intake and exhaust ports occurs and hence loss of power.

A still further loss of power and hence decreased efficiency is caused by the fact that as the blades rotate, the space between the 20 blades and the housing wall varies, due to the fact that the rotor is arranged eccentrically in the motor housing, which varies the compression of the fluid in the said space between the blades and destroys the balance of pressure 25 between the said spaces thus creating a back-pressure and resistance to the operation of the motor and even in the case of fluids of density stopping the motor.

Still further, after a blade has passed the 30 intake port and received its impulse from the fluid pressure, it is carried along by its momentum or the impulse of the next blade and of course produces no further power.

The object of my invention is to provide an 35 efficient radial blade fluid motor having simple and effective means to prevent leakage of fluid between the intake and exhaust ports of the motor by providing a surface contact between the housing wall and the periphery of the revoluble member.

A further object is to provide means in the housing walls to equalize the pressure in the spaces between the blades as they rotate, whereby further resistance to the operation 45 of the motor will be eliminated and a secondary impulse will be given each blade, after it has passed the intake port.

I attain these objects in a radial blade fluid motor having a recess in the annular wall of the housing between the intake and exhaust

ports in which a shoe is firmly secured at its end adjacent the said exhaust port and the front face of the shoe for part of its length is substantially concentric with the periphery of the rotor and in contact therewith and forms a fluid tight surface contact therewith.

Further I provide connecting fluid ducts in the annular wall of the housing and the opposite ends of said shoe communicating with said ports respectively whereby the fluid pressure between the blades may be equalized with that in the intake port.

These and other incidental objects, the details of construction and the mode of operation of my fluid motor are hereinafter fully described with reference to the accompanying drawings.

In the drawings:

Fig. 1 shows a side elevation of my motor and illustrates diagrammatically the relative centres of the revoluble member or rotor, and the radial blades therein;

Fig. 2 shows on a reduced scale an exterior view of my motor as shown in Fig. 1;

Fig. 3 shows an elevation of my motor looking in the direction pointed by the arrow 3 in Fig. 2;

Fig. 4 shows a side elevation of my motor partly in section looking in the direction pointed by the arrow 4 of Fig. 3;

Fig. 5 shows a transverse section taken on the line 5—5 of Fig. 6;

Fig. 6 shows a longitudinal section taken on the line 6—6 of Fig. 4;

Fig. 7 shows in a central longitudinal section of the various parts of my motor separated one from the other;

Fig. 8 shows a transverse section of the housing of my motor taken on the line 8—8 of Fig. 5;

Fig. 9 shows a perspective view of the annular housing of my motor;

Fig. 10 shows a perspective view of the radial blades removed from the rotor of the motor;

Figs. 11 and 12 show opposite groups, respectively, in perspective of the two halves composing the rotor; and

Fig. 13 shows the interior face of one side

plate of the housing and illustrates certain details of construction.

With reference to the figures in which my motor is shown diagrammatically, an annular 5 housing *a*, is provided, formed with a tangentially arranged intake port *b* and a radially arranged exhaust port *c*.

The housing *a* is closed at its sides respectively by plates *d* and *e* secured thereto by 10 bolts *a'*. The plate *e* is formed with a central lubricant chamber *f* on its exterior side and with a central stub-shaft *g* on its interior side. At the base of the stub-shaft *g* is formed an eccentric shoulder *h* surrounded by an annular groove *i*. The eccentricity of the shoulder *h* is towards that portion of the housing 15 between the ports *b* and *c*.

A lubricant passageway *j* leads from the chamber *f*, through the shaft *g* into the housing and ducts *g'* are provided in the said passageway, so that lubricant is evenly distributed throughout the motor, from the center outward which distribution is assisted by the centrifugal force of rotation.

25 Rotatably mounted on the stub-shaft *g* are three radial blades *o*, *p*, *q*, Fig. 10. The three blades are identical and comprise bifurcated arms *o'*, *p'*, *q'*, respectively and each arm is provided with hubs *o2*, *p2*, *q2* and the arms 30 are so spaced as to be arranged one within the other and the hubs *o2*, *p2*, *q2*, mounted over the said shaft *g*.

The blades *o*, *p*, *q*, are arranged within a 35 hollow, divided revolvable member or rotor *r*, secured together by bolts *r'*, in radial slots 2, 3, 4. The rotor *r* is provided with a central opening *s*, on one side and a central outwardly projecting shaft *t* on the other. The opening *s* is provided on its periphery with 40 an annular flange *u*, forming a bearing surface adapted to be seated in the annular groove *i* and to bear on the eccentric shoulder *h*, of the side plate *e* of the housing. The shaft *t* is journaled in the side plate *d*; on 45 antifriction bearings *v*, and is the driving shaft of the motor to which suitable gears or the like may be attached for transmitting the power of the motor to work to be done.

The radial slots 2, 3, 4 in which the blades 50 are mounted, are similar in shape and are formed wedge-shaped at their inner ends and with semi-cylindrical recesses *2a*, *3a*, *4a*, in which similarly shaped freely moving segmental bushings 10, 11, 12, are provided to 55 permit a slight pivotal movement of the blades within the rotor, during rotation, which is due to the difference in radii and the eccentricity of the housing and the rotor.

In the interior face of the housing *a* between the ports *b* and *c* is formed a shallow 60 arcuate recess 14, and in the said recess, adjacent the exhaust port *c*, an arcuate shoe 6 is secured at one end by bolts 5, and the curvature of its interior face is similar for 65 a portion of this length to the curvature of

the periphery of the rotor *r*. The depth of the recess 14 is such as to provide a space 14a between the back of the shoe and the wall of the housing. Packing 5a is inserted between the shoe and wall of the recess, at the portion 70 secured to the housing by the bolts 5.

Adjacent the intake port *b* are provided three parallel grooves or ducts 8, projecting towards and tapering to an end in the shoe 6. A single groove 8a is provided at the 75 other side of the port *b* and tapers to an end in the opposite direction.

Similar grooves 9 and 9a are provided at each side of the exhaust port *c*, respectively, tapering towards an end at one side in the 80 shoe 6, and at the other side of the port, in the housing wall.

When my motor is assembled and in operation, the blades *o*, *p*, *q*, are rotated about the 85 concentric shaft *g* by fluid entering under pressure through the port *b*, and thus are held in fixed spaced relation from the walls of the housing, approximately 1/5000 of an inch, thus eliminating frictional resistance to their rotation, but at the same time preventing substantial leakage of the fluid past them.

The rotor *r* being rotatably mounted on the shoulder *h*, which is eccentric relative to the 90 housing, is carried by the rotation of the blades, thus driving the shaft *f*.

The radius of the rotor *r* is equal to the length of the radial blades, and due to its eccentricity and to the fact that the shoe 6, is slightly spaced from the wall of the recess 100 14, and fluid entering the said space behind the shoe projects it slightly within the inner circumference of the housing, so that the rotor will be in surface contact therewith, due to the fact that the curvature of the shoe 105 is equal for a substantial portion of its length to that of the periphery of the rotor *r*, thus preventing leakage between the intake and exhaust ports, such as is the case when there is merely a point contact, formed by the 110 contact of two dissimilar curved surfaces.

However, to prevent the fluid pressure which enters the space 14a behind the shoe from creating a braking action on the rotor, the extensions of the grooves 8 and 9 in the 115 said shoe serve to permit a portion of the fluid pressure to bear against the other side of the shoe, and thus counter balance the pressure exerted against each of its sides and prevent the said possible breaking action. 120

When in operation, the volume of the space between the blades of the motor changes, first to increase and then to decrease, due to the different centers of the rotor and the housing, thus tending to cause an unbalanced pressure 125 in the spaces between the blades.

Furthermore, after a blade has passed the intake port, it has received its impulse and thereafter is carried by its momentum or the impulse of the next blade. 130

- The groove $8a$ extends from and in advance of the port b , so that as a blade has passed the said port and the space between the blades becomes slightly larger and the pressure tends to decrease but the pressure entering the groove $8a$ creates a secondary impulse as it were, that is the effect of the pressure is prolonged by building up the pressure again equal to that at the port. 5
- Then as the rotor continues to rotate the space between the blades again decreases, which tends to increase the pressure above that at the intake port and to resist the movement of the rotor, but the forward blade having passed over groove 9 , which leads to the exhaust port c and connects the space between them with the said port, permitting the excess pressure to pass ahead of the blade and be released. 10
- As the blades continue to rotate and the blade p passes the exhaust port there will be a small space between the blade and the point of contact of the housing r with the shoe, thus the grooves $9a$ serve to permit the escape of any trapped pressure between the blade and contact of the housing with the shoe. These features are important in that without the grooves the motor will not operate with fluids of higher density than air, 25 such as water, which being incompressible will lock the motor, until such trapped pressure is released. 30
- The grooves 8 , in the shoe 6 , leading to the intake port, serve to permit the escape of pressure, which may prematurely pass behind the blades before they reach the intake port b . 35
- I claim:
1. In a fluid motor of the character described including an annular housing having intake and exhaust ports and a rotor carrying radial blades, the rotor being eccentrically journaled in the said housing, the combination of a recess in the interior wall of the housing between said exhaust and said intake ports, a substantially inflexible shoe secured adjacent one end in said recess and adapted to bear against said rotor, fluid pressure spaces provided between said shoe and said wall, said spaces communicating with said ports respectively, pressure grooves provided in said interior wall extending circumferentially from each side of said ports, the pressure grooves extending from said intake port adapted to build up the pressure in the rear of each blade on each side of said intake port, and the pressure grooves extending from said exhaust port adapted to release the pressure in advance of said blades adjacent to said exhaust port, the said shoe provided with auxiliary pressure grooves at each end communicating with the pressure grooves in said wall, whereby the effect of the fluid pressure in said cavity between said wall and said shoe will be partially counteracted by the fluid pressure in said auxiliary grooves to prevent the shoe from bearing too closely on said rotor. 40
  2. In a fluid motor of the character described including an annular housing having intake and exhaust ports and a rotor carrying radial blades, the rotor being eccentrically journaled in the said housing, the combination of a recess in the interior wall of the housing between said exhaust and said intake ports, a substantially inflexible shoe secured adjacent one end in said recess and adapted to bear against said rotor, fluid pressure spaces provided between said shoe and said wall, said spaces communicating with said ports respectively, pressure grooves provided in said interior wall extending circumferentially from each side of said ports, the pressure grooves extending from said intake port adapted to build up the pressure in the rear of each blade on each side of said intake port, and the pressure grooves extending from said exhaust port adapted to release the pressure in advance of said blades adjacent to said exhaust port, the said shoe provided with auxiliary pressure grooves at each end communicating with the pressure grooves in said wall, whereby the effect of the fluid pressure in said cavity between said wall and said shoe will be partially counteracted by the fluid pressure in said auxiliary grooves to prevent the shoe from bearing too closely on said rotor. 45
  3. In a fluid motor of the character described including an annular housing having intake and exhaust ports and a rotor carrying radial blades, the rotor being eccentrically journaled in the said housing, the combination of a recess in the interior wall of the housing between said exhaust and said intake ports, a substantially inflexible shoe secured adjacent one end in said recess and adapted to bear against said rotor, fluid pressure spaces provided between said shoe and said wall, said spaces communicating with said ports respectively, pressure grooves provided in said interior wall extending circumferentially from each side of said ports, the pressure grooves extending from said intake port adapted to build up the pressure in the rear of each blade on each side of said intake port, and the pressure grooves extending from said exhaust port adapted to release the pressure in advance of said blades adjacent to said exhaust port, the said shoe provided with auxiliary pressure grooves at each end communicating with the pressure grooves in said wall, whereby the effect of the fluid pressure in said cavity between said wall and said shoe will be partially counteracted by the fluid pressure in said auxiliary grooves to prevent the shoe from bearing too closely on said rotor. 50
